ATTORNEY.

UNITED STATES PATENT OFFICE

VICTOR L. SCOTT, OF OTTUMWA, IOWA

DRILL MOUNTING

Application filed June 16, 1930. Serial No. 461,507.

The present invention relates to drilling apparatus, with particular reference to the means for mounting the drilling machine in operative relation to a post or column structure. Accordingly, the object of my invention is to devise an improved and more efficient type of drill mounting member for the attachment and support of the drilling machine in this operative relation.

Primarily, the invention comprises an improved construction whereby the drilling machine may be supported as closely as possible to the vertical axis of the post or column structure, with provision for appropriately adjusting the drilling machine in a universal manner, to accommodate the machine in any required operative position. It is also sought to devise an improved type of drill mounting which may be mounted in position upon the post or column support as easily and quickly as possible, with a minimum of effort and attention on the part of a single workman.

A further object of the invention is to provide an improved construction of this character which will afford a maximum of security in the attachment and support of the drilling machine, in addition to adapting the same to be easily and quickly mounted or removed from operative position; and with the further object of producing a supporting structure which is mechanically correct and efficient, relieving the operating parts of the drilling machine of unnecessary strain, while promoting the accuracy of the drilling operation.

With the foregoing general objects in view, as well as minor objects as will appear in the course of the detailed specification, the invention will now be described by reference to the accompanying drawing illustrating one practical embodiment of the proposed improvements, after which those features and combinations deemed to be novel will be particularly set forth and claimed.

In the drawing—

Figure 1 is an elevation, illustrating a portion of a support or column member, having attached thereto a drill mounting constructed in accordance with the present invention;

Figure 2 is a plan view of the drill mounting member, detached from the post or column;

Figure 3 is a vertical sectional view, representing a section on the line 3—3 of Figure 2; and

Figure 4 is a face view of that side of the device containing the recess or socket structure for receiving the head or disk portion of the drilling machine.

Referring now to the drawing in detail, this illustrates the drill mounting construction as comprising a body casting 5 formed as an open square bracket, designed to fit over a square form of column or post member 6 of the type using an extensible jack rod 7 as illustrated in my copending application Serial Number 461,506.

One side of the body or bracket member 5 is fitted with a clamping screw 8 adapted for clamping engagement with the corresponding face of the column 6, for securing the mounting in any desired position of vertical adjustment. The outer end of this screw 8 is provided with a swiveled handle element 9, for convenience in the manual operation of the screw 8.

One corner of the body member or bracket 5 is formed with a pair of spaced lug or bracket elements 10 in which is mounted a pivot bolt 11 for the pivotal mounting of a hand lever 12 which is formed with a ratchet finger 14 for suitable engagement with a series of ratchet teeth 15, of which a vertical series is provided in the adjacent corner of the post or column member 6 as clearly represented in Figure 1.

The ratchet finger 14 is maintained normally in engagement with the teeth 15 by the action of a coil spring 16 interposed between the adjacent corner of the body member 15 and a finger element 17 projecting upwardly from the lever 12 above the bracket lugs 10, as illustrated in Figure 1. The ratchet finger is also formed with a depending lug 14' adapted to engage a stop 14" for limiting the movement of the ratchet finger by said spring 16, and thereby facilitating the mounting of the casting 5 upon the column 6. The arrangement and construction

are such that the lever 12 constitutes a convenient lifting handle in raising or lowering the drill mounting, and the pressure applied in this operation automatically disengages the ratchet tooth or finger 14 from the ratchet teeth 15, for permitting the shifting of the body or bracket member 5, whereas upon release of the lever 12 the ratchet finger 14 automatically engages said teeth 15 for relatching the drill mounting in its new position of adjustment. After this, the screw 8 may be used, if desired, for securely locking the drill mounting in this position.

Another of the lateral faces of the body or bracket member 5 is formed with a dovetail socket for the receiving and clamping of the head or disk member 18 which is provided on the drilling machine (of which only a portion is shown as indicated by the reference numeral 19) for the purpose of mounting the machine in operative position by attachment to the post or column structure 6. This receiving socket comprises a pair of oppositely facing wedge-shaped grooves or channels 20, located at opposite sides, above and below, of the flat face 21 provided by the adjacent side of the bracket member 5 and constituting the base or bottom of the drill head receiving socket. By reference to Figures 3 and 4, it will be observed that at the open ends of the channels or grooves 20, constituting the receiving end of the socket, for admitting the disk 18, where the grooves or channels 20 are farthest apart, the first half of each channel is practically straight, with the result that these receiving portions of the channels are parallel; while the remaining or disk locking portions of the channels are curved for conforming substantially to the curvature of the disk 18, as required for clamping and locking purposes.

For forming in effect a three-point locking action, that face of the bracket member 5 opposite to the screw 8 is formed with a pair of lugs or bracket elements 23 connected by a pivot pin 24 with which is slidably engaged a latch member 25 provided with a partly curved slot 26 for engagement with the pin 24, as clearly shown in Figure 2. One end of the latch member 25 is formed with a nose or hook terminal 27 for engagement with the disk or drill head 18 at the opening into the dovetail socket, while the opposite end of the latch is threaded for the mounting of a retaining or locking screw 28. The outer end of this screw 28 is provided with a knob 29, whereby the inner end of the screw may be operated into retaining engagement with a swinging detent or takeup member 30 pivotally mounted upon a pin 31 carried by a bracket 32 on the side of the body member 5 opposite to its receiving socket. The end face of the pivoted member 30 constitutes an abutment surface 33 for engagement with the inner end of

the screw 28, whereby the hook portion 27 of the latch member 25 is operated into clamping engagement with the disk 18. The member 30 is provided with a tail piece 34 adapted to rest upon the adjacent end of the latch member 25, whereby the element 30 may be maintained in substantially horizontal (elevated) position regardless of whether the latch member 25 is in latched or unlatched position, thus insuring that the member 30 is supported at all times in operative relation to the end of the screw 28.

It will thus be seen that an efficient and conveniently operated device is provided for supporting the drilling machine in any necessary position of adjustment, and a simple and inexpensive construction takes care of all the desired objects of my invention. The drill mounting 5 is easily shifted into any position, and locked if deemed necessary by means of the clamping screw 8. When the drilling machine is to be mounted on the bracket 5, the screw 28 is loosened slightly and the member 30 is raised sufficiently to clear the latch member 25 to allow the latter to swing into retracted position as shown by the dotted lines in Figure 2, to permit the head or disk member 18 to be inserted into the socket grooves 20.

By virtue of the receiving ends of the grooves 20 being straight and parallel, it will be evident that the mere insertion of the disk into this portion of the socket lends support to the drilling machine even without any clamping of the disk by the latch 25, and that even the drilling may be proceeded with, if need be, without the clamping action of the latch member 25, since the drilling pressure is such as to force the disk 18 back into the narrow end of the socket. The construction therefore affords what may be termed a one-man proposition, since the machine can be mounted and held in place without necessarily being tightened or clamped, or this tightening operation for clamping the machine can be attended to without any difficulty by a single operator, since there is no material danger of the machine becoming dislodged, and the clamping means provides a quick-acting clamp adapted for easy operation and securely clamping action for locking the disk 18 within the socket. The same is true as regards the removal of the machine from its supported position, the latch 25 being quickly disengaged by a retracting operation of the screw 28, thereby disengaging the hook element 27 from the disk 18 (as illustrated by the dotted lines in Figure 2).

Thus a drill mounting structure is provided which permits all necessary adjustments of the machine's position, either as to variation in the elevation of the machine upon the post or column support 6, or pivotally about a vertical axis (by movement with said post around its vertical axis, as explained in my

aforesaid application), or vertically about a horizontal axis within the dovetail socket, after simply loosening the clamping element 25, as will be readily and clearly understood. It is of course evident that the machine can be swung in a complete circle by means of the described mounting structure and yet locked rigidly and securely in any desired position.

The accuracy of adjustment, as well as the 10 security of the supporting functions provided by the described construction, promotes not only greater drilling speed and accuracy in the drilling operation, but relieves any unnecessary strains upon the tools, such as the 15 augers, cutters and other drill parts, which are often caused by faulty alinement or a supporting structure which is not entirely rigid. Such accuracy and rigidity in the supporting structure are material factors in the reduction 20 of maintenance cost and elimination of frequent repairs.

While I have described what I now regard as the preferred mode of practicing my invention, and embodying the improved features 25 of construction, I desire to reserve the right to make such changes or modifications as may fairly fall within the scope of the appended claims.

What I claim is:

1. A drill mounting for drilling machines comprising a bracket member formed with a drill disk receiving socket, a pivoted and sliding latch member mounted opposite the receiving end of said socket for clamping engagement with the disk, a clamping screw carried by one end of said latch member for actuating the same into latching position, and a movable abutment element carried by said bracket member in position for engagement with one end of said screw.

2. A drill mounting for drilling machines comprising a bracket member formed with a drill disk receiving socket, a pivoted and sliding latch member mounted opposite the receiving end of said socket for clamping engagement with the disk, a clamping screw carried by one end of said latch member for actuating the same into latching position, and a movable abutment element formed with a projection supported by said latch member for maintaining said element in position for engagement by one end of said screw.

In witness whereof I hereunto affix my signature.

VICTOR L. SCOTT.
